2,534,189

VACUUM CLEANER NOZZLE

Edward A. Wright, Elk Creek, Calif.

Application June 15, 1944, Serial No. 540,479

2 Claims. (Cl. 15—415)

1

My invention relates to attachments for use in connection with vacuum or suction cleaning apparatus and particularly for use in the cleaning of pile rugs and fabrics.

This application is a continuation in part of, abandoned application S. N. 459,349, filed September 23, 1942.

The problem in the cleaning of such fabrics and rugs is to remove the dirt (particles of sand, grit, etc.) which has fallen on the surface of the rug and then has worked its way down into the pile towards the backing or base of the rug. As these particles accumulate in the pile of the rug, they tend to have an attritional effect on the pile and to destroy the rug. Hence, it is important in cleaning the rug to remove this dirt. It is also important to do it without destructively beating the pile, as any mechanical beating wears the carpet.

One of the objects of my invention is to provide a construction of nozzle which, through controlled directions of air flow, will impart to the rug pile successive agitation, shaking and lifting and tending to straighten up the pile solely by a number of almost instantaneous changes in the controlled directions of air pull.

Another object of my invention is to provide means for imparting successively to the pile in a given area of the rug radically opposed air pulls, like along the legs of a V, so that embedded dirt which may be trapped by the pile against removal in a straight upward pull or a pull at one angle, will be freed and go along with the current of air moving in the direction in which the pile does not hinder it.

Another object of my invention is to provide a type of nozzle which, in addition to subjecting the pile to a rapid flow of air tending to lift the dirt out of the rug, will also tend to separate adjacent rows of the pile and expose to the rapid flowing air streams whatever dirt and grit lies in between the pile.

Another object of my invention is to provide a device of the character referred to which is capable of being applied to the suction heads of any suitable vacuum producing apparatus.

Another object of my invention is to provide a novel vacuum cleaner which operates according to a new principle for the treatment of pile fabrics wherein there is induced the flow of generally horizontal, inwardly converging air currents into a central area in the pile from two opposite lateral directions to form a single generally upwardly moving air current, then dividing the upwardly moving air current into two oppositely,

2

upwardly and outwardly directed air currents to effect a spreading apart of the pile, and lifting the dirt and grit from said pile by that vacuum induced upwardly moving air current.

5 Another object of my invention is to provide a device which is simple in manufacture, which has no moving parts such as a rotating brush to injure the rug or get out of order, and yet achieves agitation of the rug pile in a novel and harmless manner.

Other objects of my invention will appear more fully hereinafter.

The invention consists substantially in the construction, combination, location and relative 15 arrangement of parts, all as will be more fully hereinafter set forth, as shown in the accompanying drawings and finally pointed out in the appended claims.

In the drawings:

20 Fig. 1 is a view in perspective, the end of the nozzle being broken off to show a cross-section of a construction of attachment embodying the principles of my invention;

Fig. 2 is a bottom plan view of the device of

25 Fig. 1;

Fig. 3 is a view in perspective of the device of Fig. 1;

Fig. 4 is a view in perspective, the end being broken off to show a cross-section of a single 30 unit device embodying my invention;

Fig. 5 is a bottom plan view of the device shown in Fig. 4;

Fig. 6 is a vertical end view of the device shown in Fig. 4; and

35 Fig. 7 is a schematic showing of the various currents created.

Like reference numerals have been employed in the several figures to facilitate the description.

My invention can best be understood by referring briefly to the present day type of vacuum cleaner nozzle which usually has a single wide opening. As the nozzle is moved back and forth across the rug, air rushes in under the leading and trailing edges and then upward through the carpet pile. This compresses the pile beneath the opening in toward the center and aids the pile in holding entrapped dirt. No advantage is taken of the valleys formed adjacent each outside edge of the nozzle because there is no upwardly 45 directed air current at these points to lift out the exposed dirt. While the air currents beneath the leading and trailing edges are generally horizontal toward the center of the nozzle, and while the air current near the center of the nozzle is 50 generally upward, the transition in direction of

the air currents and their effect on the carpet pile is so gradual that the pile is not laid open. It therefore can get a new grip on displaced dirt particles and resist the pull resulting from the change in direction of the air current.

My invention, on the other hand: (1) agitates the pile by air, (2) spreads apart the agitated pile from its adjacent rows of pile, and (3) subjects the agitated pile to a strong upward flow of air.

My method of treating pile type fabrics includes the steps of (1) inducing a flow of generally horizontal inwardly-converging air currents from two laterally opposite directions toward a central area where they meet to form a single, generally-upward-moving air current; (2) dividing this inwardly moving air current into two oppositely directed upwardly-and-outwardly-flowing air currents, thus, effecting a spreading apart of the pile; and (3) lifting the dirt and grit out from the parted pile into these upwardly moving air currents.

The features of my invention which carry out this method may be embodied in a wide variety of structures and arrangements of details without departing from the spirit and scope of my invention. While, therefore, I have shown and described, pursuant to U. S. Revised Statutes, section 4888, various operative and practical embodiments and forms of devices, I do not intend to limit my invention to the specific apparatus and to the details shown.

One form of apparatus is shown, in Figs. 1, 2, and 3, where there is a hollow body nozzle member 10 having the usual neck 11 to which is secured a hose or handle connected to the source of vacuum. The body member has inwardly sloping sides 12, which, at their inner edges 13, in cooperation with angular member 19, form narrow air inlet openings 14. The width of openings 14 should be narrow in proportion to their depth so that the air entering will be given a definite directional pull.

Arranged within the body member 10 are inner flared members 15 mounted adjacent the inlet openings 14 with their lower edges 16 projecting into the inlet openings 14 whereby the air flow entering the openings is divided and deflected into forwardly and rearwardly directed streams, one pair of currents passing up the conduits 17 and the other pair up the conduits 18. Each opening 14 just described may be regarded as a pair of openings treating each edge 16 as a partition.

These divided directional air streams flowing into channels 17 and 18 tend to separate the pile of the carpet below 16, to open a V-shaped trough or valley, and thereby free any grit, dirt, etc. lying therein. When to this action is added movement of the nozzle over the carpet, a very beneficial agitation of the pile results. As described above, this imparts successively to the rug pile a number of instantaneous changes in the direction of air pull so that embedded dirt which may be trapped by the pile against removal in a straight upward pull or a pull at one angle will be freed and go along with the current of air moving in the direction in which the pile does not hinder it.

To facilitate entry of air so it can flow in the direction of arrows A' and A² through channel 20 in member 19, the ends of housing 10 are relieved at 37.

The form of device shown in Fig. 4 is identical in operating principle with the one just described except that it has only a single unit.

This form of the device is substantially the same and provides the conduits 17 and 18 which produce the opposite outwardly and upwardly directional pulls which tend to subject the embedded dirt to a flow of air at least in one direction where the dirt can be moved without hindrance from the pile.

For rugs of different length pile, it may be considered preferable to have means for changing the relative position of the edge 16 and edges 13.

To accomplish this adjustment, many different forms of mounting can be arranged for the inner member 15. In Fig. 4 I have illustrated one which comprises rods 25 which are held for rotational movement in member 15 by threads 26. They are mounted in housing 10 through holes 27 and are yieldingly secured against upward movement by spring 28. Turning of rods 25 will raise or lower the edge 16 with relation to the edges 13 of the air inlet opening 14. Springs 28 also serve to hold the parts against vibration.

An alternative arrangement, whereby the member 15 is allowed to float on the carpet, that is, to bear on it by gravity and thus adjust itself to proper position, is accomplished by removing the springs 28 and turning the rods 25 upwardly to the point which allows member 15 to assume its lowermost efficient operating position. Then, as the nozzle is moved over the carpet, member 15 will rise and fall under the influence of the surface.

Another alternative is shown in Fig. 3, where the members 15 are adjustably supported by screws 36 in vertically extending slots 35 in the ends of housing 10.

It is optional whether means are provided for adjusting the inner member 15 as it has been found in practice that a single setting of the edges 13 and 16 will be generally satisfactory for most types of pile fabrics to be cleaned in the average home.

The operation of the vacuum cleaner will now be described with particular reference to the type of device disclosed in Fig. 1. As the nozzle 10 is moved over the rug, the suction current being on, air is being drawn in over and through the carpet from each edge 13 of the sweeper head 10 and also through the relieved opening 37 and the channel 20. These air currents are shown by the arrows A, A¹, A², and A³. Each individual pile tends to follow the air current to which it is subjected. These inwardly sweeping air currents meet at the center of the narrow air inlet opening 14. Then they tend to move upward into the nozzle. As they move upward, they are divided, almost immediately, into one current passing up through the passageway 17 and another current passing up through the passageway 18. At any one moment, the pile below the opening 14 is thus laid open, forming a valley so that the dirt can be drawn up into the passageways 17 and 18.

As applicant's device is passed to the right over the rug, the air current under the leading edge 13 is horizontal towards the rear (to the left in Fig. 1) through the rug pile and through any space which may exist between the bottom of the nozzle and the floor. However, as the first narrow slot 18 passes over the point on the rug, the direction of the air current suddenly changes approximately 135° in the direction of the opening 18. (See the diagram in Fig. 7.) There is no substantial drop in air velocity at this time, because of the narrow cross sectional width of the passageway 18 and because of its cross sec-

tional length, which prevents the main air current from taking any short cuts and forces it to flow up the passageway 18.

Then, as the dividing point 16 between the passageways 17 and 18 passes over the given point in the rug, the direction of the air current is suddenly changed, approximately 90°, and the air passes up the passageway 17. After the passageway 14 is passed, the air current is once again changed approximately 135° and becomes horizontal in the direction of A¹.

In the type of device shown in Fig. 4, this comprises the complete operation cycle. However, in the type of device shown in Figs. 1, 2, and 3, the cycle is repeated as the second pair of openings 18 and 17 pass over the rug. This cycle is repeated for as many sets of channels as are embodied in the nozzle.

The sudden radical changes in the direction of the strong air currents tend to shake loose dirt particles and pull them away before the pile fibers have time to get a new grasp on them and to increase inertia against the pull in the new direction. The opposite directional ducts 17 and 18 tend to open up the pile and to lift it up and straighten it rather than to compress or mat it. Thus, the dirt far down in the pile is drawn up by the force of the air currents alone. There is no necessity for any mechanical beating which tends to break the rug fibers.

The action of the rug which is described is clearly visible to the eye on rugs having a soft pile. On rugs having a stiff pile, the action is not always visible, but it is always present.

Having now set forth the objects and nature of my invention and constructions embodying the principles thereof, what I claim as new and useful and of my own invention, and desire to secure by Letters Patents, is:

1. In a vacuum cleaner suction head adapted for treating pile fabrics to a substantial depth with a vacuum induced upward air sweeping action, a body member with a working face having two narrow closely spaced, adjacent parallel slits

to engage the surface of the pile fabric material, and a pair of outwardly diverging substantially parallel-walled conduits in said body member, defined in part by a transverse partition having a narrow imperforate lower edge extending into the plane of the working face, said conduits communicating at their upper wide apart ends with the source of vacuum and with their lower ends connected to said closely adjacent slits where they open onto said working face, whereby only a vacuum induced flow of air is present which sweeps through the fabric pile tending to cause the pile to divide as the upwardly flowing air stream divides and bends outwardly into said conduits thereby tending to lay apart the pile between said slits and exposing any entrapped dirt and grit to the full upward sweep of the vacuum-induced upwardly-flowing air current to lift out any dirt and grit therein.

2. The device of claim 1 adapted for treating pile fabrics with vacuum induced upward sweeping currents simultaneously at a plurality of spaced apart points in which said body member has a plurality of said transverse partitions, each of which is bounded by said adjacent parallel slits and said outwardly diverging conduits.
